UNITED STATES PATENT OFFICE.

ALFRED J. ELLIS AND CHARLES E. NELLIS, OF WOODCLIFF-ON-HUDSON, NEW JERSEY,
ASSIGNORS TO A. J. ELLIS, INC., A CORPORATION OF NEW JERSEY.

APPARATUS FOR FORMING SHEET METAL INTO SHAPES.

1,142,242.

Specification of Letters Patent.

Patented June 8, 1915.

Application filed January 30, 1911. Serial No. 605,424.

To all whom it may concern:

Be it known that we, ALFRED J. ELLIS and CHARLES E. NELLIS, citizens of the United States, residing at Woodcliff-on-Hudson, 5 township of North Bergen, in the county of Hudson and State of New Jersey, have invented certain new and useful Improvements in Apparatus for Forming Sheet Metal into Shapes, of which the following 10 is a full, clear, and exact description.

This invention relates to apparatus for rolling sheet material into forms adapted for use as molding and the like, such forms being of any desired configuration in cross- 15 section and of indefinite length.

By the means disclosed herein a strip of sheet metal or the like may be molded or rolled into the desired form by passing the same through a series of fluting rolls of different shapes, the material being preferably drawn through the said rolls and thereby maintained straight after delivery therefrom; while if inadvertently or for any reason deformed by longitudinal curvature, 25 such material is straightened by the tension to which it is subjected.

A further object of our invention is to so conduct the rolling operation proper that such deformation will be substantially obviated.

Another object of the invention is to facilitate the process of rolling in the manner above described by providing means whereby the said rolls may automatically 35 center or align themselves, so to speak; the material itself being used as the means for displacing successive rolls laterally with respect to the material to a greater or less extent during the initial operation of the 40 mechanism employed, by which action a series of sets of rolls are definitely aligned, and the shape to be rolled is thereby delivered from the rolls substantially free from distortion.

45 Other objects of our invention will be hereinafter referred to and more particularly set forth in the appended claims.

In the accompanying drawings which 50 form a part hereof and which exemplify one form of apparatus adapted to produce the product in question: Figure 1 is a side elevation of the said apparatus. Fig. 2 is a plan of the same. Fig. 3 is an elevation of the rolling mechanism proper drawn to 55 larger scale. Fig. 4 is a plan of the same.

Fig. 5 is a fragmentary section showing a portion of the finishing rolls with the finished material, in section, therebetween.

Like characters of reference designate 60 like parts throughout the several views.

Referring first to Figs. 1 and 2, the complete apparatus is therein shown to consist of two principal parts; namely a rolling mill shown at the left hand side of each of said figures and a draw-bench at the right hand 65 sides of the same. The mill comprises a suitable supporting plate 1 mounted on legs 2 carrying a grooved bed-plate 3 which may be secured to the supporting plate in any suitable manner, the grooves 4 in the bed-plate being preferably laterally undercut as at 5. A number of these grooves are provided, more or less of which will be used according to the complexity of the shape to be rolled. In rolling the shape 6, for example, shown in Fig. 5, in section, five pairs 70 of rolls are employed, the spindles of these rolls being journaled in suitable boxes 7, which boxes are preferably all substantially the same in form and in dimensions and 75 have the vertical edges thereof recessed as at 8 for the reception of the sides of the uprights or housings 9. The lower extremities of these housings are dove-tailed so that the same may be entered into the grooves 4, and 80 when positioned therein, will be held securely against movement other than that in the direction of said grooves. After the housings 9 have been aligned, they are locked 85 against such movement by the trapezoidally 90 shaped blocks 10 which are slid into the grooves and abut against the sides of said housings. Set-screws 11 are preferably provided in each of these blocks whereby they may be firmly clamped against displacement. The boxes 7 are adapted to be slid 95 freely up or down between their respective housings and the lowermost boxes are spaced from the upper surface of the bed-plate at varying heights by any suitable means, such, 100 for example, as the small jacks 12. The upper boxes may be correspondingly spaced from the lower by similar means and the upper extremities of the housings are laterally recessed to form dovetail shaped grooves 13 105 which are adapted for the reception of the correspondingly formed extremities of the tie-bars 14.

The rolls are slidably mounted on threaded spindles 15, the respective extremities of 110

which are preferably slightly reduced in diameter and are journaled as aforesaid in the boxes 7, each spindle being provided upon either side of its roll with a nut 16. Lock-nuts 17 may further be provided, if desired. Nuts 16 may be turned freely away from the rolls so as to leave the latter free for longitudinal displacement when desired, for reasons hereinafter referred to. For convenience the first set of rolls are respectively designated 18 and 19; the second set 20 and 21; the third, 22 and 23; the fourth, 24 and 25; and the fifth, 26 and 27; the even numbered rolls being the lowermost in each case. The sheet material 28 is preferably provided in the form of a long strip which may be coiled as at 29; the coil of material being supported in any suitable manner, as by means of a rod 30 which extends between the angle bars 31 which project from the rear end of the bed-plate, said bars being secured thereto in any suitable manner, as by means of the trapezoidally shaped blocks 32 and bolts 33. The material to be rolled first passes between suitable guides, as for example, the rollers 34, which may be mounted in suitable recesses provided in guide bars 35. These latter are in turn mounted upon a cross-bar 36 which is secured to the first pair of housings by means, for example, of suitable clamps 37, the latter being drawn toward the sides of the housings to which they are secured by means of bolts 38. The cross-bar 36 is preferably slotted as indicated in Fig. 4, wherein the upper side of the slotted central portion is broken away at 39 to expose the strip of sheet material passing through the said slot, while the under side of said slotted portion is indicated in dotted lines at 40. The guide bars 35 are centrally recessed for the reception of cross-bar 36, as indicated at 41, and are secured thereupon in any suitable manner. The material passes through these guides to the first rolls 18 and 19; and in carrying our novel process into effect we have found it highly advantageous to secure only one of these rolls, preferably the bottom roll 18, against longitudinal displacement by clamping it between its nut 16; the upper roll 19 being free to rotate unrestrainedly upon its spindle and to center itself with respect to the lower roll. The upper rolls are held down almost in contact with the lower rolls, leaving just sufficient space for the material to pass therebetween, by means of the screws 42, which are threaded through the tie-bars 14 so that the material is firmly held between each set of rolls as it passes therethrough. In rolling the particular form shown in Fig. 5 the initial operation upon the material, which is performed by the first set of rolls, is the formation of a trough or crease 43 in the sheet and the curving of the respective sides thereof in conformity with the curved por-

tion 44 of roll 19. Thereafter the material passes between rolls 20 and 21, where the groove is made still deeper and the curvature of the sides more pronounced. Rolls 20 and 21 are preferably both left free initially to adjust themselves laterally with respect to the material passed therebetween from the first set of rolls, so that there is no tendency to impart a lateral curvature to the strip, as would be the case if the second set of rolls were initially clamped against such lateral displacement and the centers thereof should happen to be slightly out of alignment with the centers of the first set of rolls. The material passes from the second set of rolls to the third set where, in producing the particular product exemplified, said third set form the flanges 45, such flanges of course not being inwardly directed as in the finished product, but projecting laterally as shown in Fig. 4. These rolls also serve to form the corrugations disposed upon either side of the central groove 43. Here again the respective rolls are left free to adjust themselves with respect to those above mentioned by initially spacing the clamping nuts a sufficient distance away from the respective ends of the roll. The material then passes to the fourth set of rolls where its sides are curved downwardly in this instance, the flanged portions being thrown around so that they are in approximate parallelism. Finally the material passes to the finishing rolls which have substantially the configuration shown in Figs. 4 and 5; the lower roll 26 being quite narrow so that it is enabled to pass freely out of the aperture left between the flanges 45 when the same have been driven around into the position shown in Fig. 5, the upper roll effecting this action by co-acting with the lower roll to more sharply bend the corrugations 46. Of course these last sets of rolls are also free, at least initially, to displace themselves longitudinally so that the centrally disposed flanges of all of the upper rolls and corresponding recesses or grooves of the lower rolls are arranged in the same plane. Of course it will be understood that it is not essential that the product have the configuration shown in Fig. 5 and that the rolls may be modified in accordance with the form of material to be produced. In any event, however, we prefer to leave all of the succeeding rolls free to displace themselves laterally with respect to the material and thereby align themselves; one of the first rolls alone being secured against displacement to, in effect serve as a guide for the others.

It will be observed too that the successive rolls are disposed at varying levels. This is desirable when rolling shapes of the character in question, since when the metal is fluted, corrugated, or troughed, it has a tendency to distort or curve around verti-

cally one way or the other according to the indentations, troughs or corrugations formed therein, and this tendency may be counteracted in a great measure by properly 5 elevating or depressing the following set or sets of rolls. In rolling the shape shown in Fig. 5, for example, the rolls are arranged at the levels shown in the drawings. By reason of this arrangement the material 10 tends to emerge from the last set of rolls substantially without lateral distortion or curvature, and hence it is possible to manufacture the product by driving the roll-train direct by any of the usual means employed 15 to this end, if desired, but we prefer to pass the material between the respective sets of rolls by drawing the same, and to this end may provide, for example, the draw-bench already referred to. This draw-bench may 20 be of the usual construction so that only a brief description of the same will here be given. It consists of the rails 50 which are preferably much longer than those shown in Figs. 1 and 2, a section being broken out of 25 the rails, and also the other parts of this portion of the device, at 51, in order to save space. The rails 50 are preferably I-beams and are secured together by suitable frames, the frame adjacent the roll-train being des- 30 ignated 52 and that at the rear of the draw-bench being broadly designated 53. Between these rails is disposed the channel 54 over which the chain 55 is adapted to slide. At the left hand end of the said rails and se- 35 cured to the webs thereof is a suitable casting 56 which serves as a bearing for the spindle of the idler-sprocket 57 over which passes the chain 55. The rear end of this chain correspondingly passes over a sprocket 40 58 which is mounted on the shaft 59, said shaft being journaled in bearings carried by or forming a part of the frame 53. Shaft 59 carries upon one extremity the gear 60 which is in mesh with a pinion 61 mounted on a 45 countershaft 62 also journaled in frame 53, this shaft carrying upon the end opposite said pinion a gear 63 which correspondingly meshes with a pinion 64 mounted on the driving shaft 65 which is journaled in the 50 forward end of frame 53. This shaft carries fast and loose pulleys respectively designated 66 and 67, these pulleys in turn being driven by a belt 68 which is provided with a belt-shifter 69 of any ordinary con- 55 struction. The shifter rod 70 passes through suitable apertures in the webs of the respective rails and is adapted for reciprocation by a bell-lever 71, which latter is pivoted at 72 to a suitable bracket 73 carried upon the 60 side of the outer rail as shown in Fig. 2. A rod 74 mounted in suitable brackets 75 is longitudinally displaceable by means of the lever 76, the handle of which lever is conveniently disposed adjacent the roll-train, 65 this rod being connected at its farther ex-

tremity with the bell-lever 71 so that when lever 76, which is pivoted at 77 to a suitable bracket 78 carried by one of the legs of the draw-bench, is moved in one direction or the other, the belt 68 will be correspondingly shifted to the loose pulley, or vice versa. Lever 76 therefore affords means for controlling the movement of chain 55. The jaws 79 and 80 are mounted upon suitable rollers 81-82 which ride on the upper faces 75 of the rails. These jaws are of the usual type, being adapted to be opened by lever 83 and are adapted to be drawn along from the forward to the rear end of the rails when the pivoted hook 84, which is secured 80 to the outer extremity of the link 85, is engaged with one of the pins 86 of the chain, link 85 of course pulling lever 87 which is pivotally mounted upon the spindle 88 upon which rollers 81 are mounted, to the rear, 85 and thereby through the instrumentality of link 89 drawing the jaws 79-80 firmly together.

In operation after the material has been passed between the respective sets of rolls, 90 the extremity thereof is gripped between the jaws 79-80 by rotating lever 83 downwardly, the hook 84 is thrown over so that it may engage one of the pins 86 and the draw-bench mechanism is started by means 95 of lever 76. Thereafter the jaws 79-80 are drawn still more tightly together, firmly gripping the material therebetween and are pulled by the chain toward the rear end of the bench, rapidly and efficiently pulling the 100 material through between the rolls which form the same into the required shape in the manner above described, and the tension under which the material is placed, after being formed by this operation, not only main- 105 tains the same perfectly straight, but if any lateral distortion has occurred, serves to substantially remove the same. After the ma- 110 terial has adjusted the rolls in the manner described, the lock-nuts may be screwed up against their respective rolls, if desired, which will serve to prevent any accidental displacement of said rolls in operation.

To the best of our knowledge it has never 115 been possible heretofore to cold roll com- plexly fluted thin metal strips or moldings of the types in question so that such strips shall be practically perfectly straight when formed, since it has always been found necessary hitherto to straighten out the 120 products in a separate subsequent operation. We are aware that it is old to form pipes and tubing by pulling sheet material through cross rolls, but the product pro- 125 duced by our process is practically non-tubular and is formed from thin sheet ma- terial, the same being in most instances cor- rugated in analogous fashion to the product exemplified and being straight when de- 130 livered from the machine. This straight-

ness of the product, we believe, is due to the perfect alining of the rolls, accomplished in manner aforesaid; to the step by step counteraction of any tendency to laterally distort by varying the heights of successive sets of rolls; and finally to the drawing of the product through the rolls.

Having described our invention, what we claim, is:

- 10 1. In an apparatus for bending sheet material into shapes, a roll train comprising a plurality of pairs of fluting rolls of different conformations and disposed at different elevations for successively shaping the sheet of material, each of said pairs of rolls being disposed at an elevation with respect to the other pairs of rolls such that any longitudinal curvature of the sheet of material caused by the shaping of the same between one pair of rolls will be straightened upon the sheet of material passing through the next pair of rolls and means for drawing the sheet of material through said rolls.
- 15 2. In an apparatus for forming sheet material into shapes, a roll train comprising a plurality of pairs of fluting rolls arranged to successively engage a sheet of material, supports for the same, said rolls being free to move laterally on said supports, means for drawing the material through the rolls, the adjustment of a roll with respect to the others being controlled by the conformations formed in the sheet of material.
- 20 3. In an apparatus for forming sheet material into shapes, a roll train comprising a plurality of pairs of rolls arranged to successively engage a sheet of material, one roll of the first pair being fixed against lateral

movement, the other rolls being free to move laterally, the positioning of the other roll of the first pair and the remaining rolls of the train being controlled by the conformations in the sheet of material, and means for drawing said material through said rolls.

4. In an apparatus for forming sheet material into shapes, a roll train comprising a plurality of pairs of rolls arranged to successively engage a sheet of material, one roll of the first pair being fixed against lateral movement, the other rolls being free to move laterally, the initial positioning of the other roll of the first pair and the remaining rolls of the train being controlled by the conformations in the sheet of material, and means for drawing said material through said rolls, together with means for locking said rolls after they have been positioned.

5. An apparatus for forming sheet material into shapes, a roll train comprising a plurality of pairs of rolls arranged to successively engage and hold a sheet of material, each pair of rolls being of a different conformation and disposed at a different elevation, supports for said rolls, said rolls being free to move laterally on said supports, and means for locking one of the rolls of the one pair to engage the sheet of material and hold it against lateral movement.

In witness whereof, we subscribe our signatures, in the presence of two witnesses.
